3 Claims. (Cl. 40—127.1)

1

This invention relates to a method and apparatus for sky writers, particularly to that type of sky writing where a number of planes flying in formation cooperate in producing the letters.

According to the present invention a number of planes fly in parallel and with substantially equal speed following a straight line so that they are, at all times, aligned at right angles to the direction of flight. Each plane is equipped with smoke emitting apparatus. Emission of smoke is controlled to occur at short, regularly spaced time intervals. Means are provided to select these intervals for each plane prior to its flight so that the desired letters will be formed by the cooperation of the several smoke outlets. Each plane is provided with such a selector system, and one plane is further provided with a control for the synchronization of the performance of the several smoke outlets in the plurality of planes. Alternatively, this synchronizing or control signal may be provided by a station on the ground.

It is known to use a plurality of planes for forming the letters, each plane being assigned a certain part of each letter. In these prior art methods, records, similar to those used in player pianos, consisting of a blank provided with slots shaped in the pattern it is desired for the particular plane to write, are disclosed. This slotted blank is used to make and break an electric connection, thereby generating signals of a desired duration and placement. These signals are generated in a particular plane and are then transmitted to the other planes over separate channels, each signal being transmitted to the plane for which it is intended. Thus, a number of channels, one for each controlled plane, must be provided.

According to the present invention, it is not necessary to provide a plurality of channels, equal to the number of controlled planes, identical signals being sent to all participating planes. The signals transmitted according to the present invention serve to synchronize the various patterns for the different planes, the patterns to be determined by a selector system in each plane. Since an identical synchronizing signal is transmitted to all planes, the system according to this invention requires only one transmitting channel, independently of the number of participating planes. Hence, if in the prior system the different patterns are transmitted over adjacent radio channels, a wide transmission band will be necessary, whereas the present method will need only a small fraction of this band which is made

2

applicable to the entire number of participating planes. It will thus be appreciated that the separation of the two functions, the synchronization and the selection of the patterns, constitutes a considerable advantage over the prior art.

It is a further advantage of the present method that the selection is accomplished by standard commercially available parts, such as, for instance, a multi-contact switch, whereas the prior systems required specially produced records. Changing from one message to another hence required the pattern record to be replaced so that separate records must be made for each message. The multi-contact switch, or other selector mechanism, used in the system according to this invention, will accommodate any message or other shapes it is desired to form.

Other advantages of the present method will become apparent in conjunction with the following specification and drawings.

Fig. 1 is a schematic view illustrating the formation of letters according to the present invention.

Fig. 2 is a front view of the panels carried by a plurality of planes.

Fig. 3 is a block diagram of the apparatus contained in the control plane and in the controlled planes, respectively.

Fig. 4 is a schematic diagram of part of the electronic apparatus in the control plane.

Fig. 5 is a schematic diagram of part of the electronic apparatus in each of the controlled planes.

Fig. 6 is a schematic diagram of the selector system and smoke control units.

Fig. 7 is a view of a plug-board showing the connections to stepping switches.

One manner in which the script is formed is illustrated in Fig. 1. Each letter is composed of suitably arranged short parallel lines of equal length, and the thickness of the heavy strokes in the letters may be approximately equal to the length of these short lines or a multiple thereof. The numbers to 150 in the first row of this figure indicate time intervals during which smoke may or may not be released. The numbers 1 to 7 in the first vertical row indicate the plane from which the smoke is emitted. It will be seen that any pattern composed of blank and smoke spaces may thus be ascribed to all planes, the patterns for two different planes being, in general different.

In the particular embodiment shown, the word "Buy" is outlined. The first plane will have to

emit smoke for the time intervals 1, 2, 3, 4, 9, 10, 11 and 17, no smoke being released at any other time.

Fig. 2 shows the selector panels 34 for the seven planes, the open circles indicating that no plug is inserted into the particular socket and the connection is broken, while the filled-in circles indicate insertion of the plug. Each plane carries its own panel; the number of each plane is indicated on the drawing. It will be seen that the selector panels are set up to make a connection for all those time intervals for which smoke is to be emitted from the associated plane, such as plugs 1, 2, 3, 4, 9, 10, 11 and 17 of the panel in plane 1; all other plugs are disconnected.

Fig. 3 shows a block diagram of the equipment, illustrating on the left-hand side the apparatus in the control plane, and on the right-hand side the apparatus in each of the controlled planes. Alternatively the audio oscillator 2, electronic switch 3 and transmitter 4 may be installed on the ground, and all planes made to be controlled planes.

In the embodiment shown in Fig. 3, an audio frequency oscillation is generated by the audio oscillator 2 in the control plane. This oscillation is regularly interrupted by an electronic on-off switch 3 for approximately 0.6 second every 0.6 second. This time interval results in the desired length for the lines 1 if the planes fly about 150 miles per hour. However, a different timing sequence may be preferred. The audio frequency pulses will be fed to the transmitter 4 which comprises a carrier generator, a modulator, and a transmitting antenna, all of conventional design and not shown.

The control unit 5 derives its input from the on-off switch 3 and advances the step selector system 6 by one step each 1.2 seconds, in the embodiment described, by means of a relay and solenoid arrangement more fully described and explained in connection with Fig. 4.

Referring again to Fig. 3, the step selector system 6 having been advanced, it will either make or not make a connection depending on the setting of the associated plug on the corresponding panel of the control or controlled plane, illustrated in Fig. 2. If a connection is made, a smoke control 7 will be operated and smoke will be emitted.

A similar control unit 5A, selector system 6A and smoke control 7A are incorporated in each of the other planes, where they are controlled by a signal transmitted from the control and demodulated in the receiver 8.

Figs. 4, 5 and 6 illustrate details of a particular embodiment of this invention. Fig. 4, the control plane audio oscillator, electronic on-off switch, and switch control unit, shows the oscillator, comprising tubes 11 and 12, generating the audio oscillation. The output of this oscillator is fed to an amplifier tube 13. The grid bias of tube 13 is provided by a multivibrator 14, the output of which is rectified in tube 15 to give pulses, and interrupts the plate current of tube 13 for regular intervals of 0.6 second spaced 0.6 second.

This regularly interrupted audio frequency wave is fed to a conventional transmitter, comprising a carrier generator, a modulator, if necessary an amplifier for the modulated carrier, and an antenna; the transmitter is not shown.

The rectified multivibrator output also oper-

ates relays 16 and 17 in the plate leads of tubes 18 and 19, respectively. Both tubes are normally cut-off, and both relays are normally open. Relay 16, when closed by a positive pulse on the grid of tube 18, applies 12 volts to the terminals A and F on plug 26 connecting to the selector system and smoke control unit shown in Fig. 6.

Relay 17, when closed, connects 12 volts to the lamp 21, flashing on every 0.6 second for 0.6 second, indicating that the multivibrator and rectifier operate satisfactorily.

Voice-tone switch 22 is operated by the pilot to open the relay 23 if the pilot of the control plane wants to communicate with the other pilots. Opening of this relay will interrupt current through tubes 18 and 19, cutting off all smoke supplies.

The circuit elements and their mode of operation of the audio oscillator and electronic on-off switch shown in Fig. 4 will now be described in more detail. Tubes 11 and 12 with the associated circuit elements shown in Fig. 4 are connected together in such a manner as to form a conventional sine wave oscillator. The output voltage developed across plate load R9 is coupled through C-5 to a voltage divider potentiometer R-11. Such portion of this voltage as is desired is impressed on the grid of tube 13 and amplified. This amplified voltage is then fed to the input of the radio transmitter connector 50. Tube 13 is used to key the modulation signal. The keying is accomplished by periodically biasing the grid of 13 to cutoff.

The grid of tube 13 is connected to ground through resistors R-12 and R-24; the cathode is connected to ground through R-13 and the contacts of relay 23. C-8 is a bypass for R-13. Positive voltage from terminal B is applied to the plate of tube 13 through R-14. With the contacts of relay 23 closed, plate current will flow and tube 13 will amplify the voltage applied to the grid through capacitor C-6. This amplified voltage is applied through contact plug 50 to the input of radio transmitter 4 and modulates same.

The grid of tube 13 is also connected to the plates of diode 15. Tube 14 which is a conventional flip-flop circuit or square wave oscillator is coupled to the cathode of diode 15 through C-12. Whenever the negative half of the square wave appears at the cathode of 15 the diode conducts and applies a negative voltage to R-24. Since the grid of tube 13 is connected to ground through R-24 a negative voltage on R-24 of sufficient amplitude will cut off tube 13. By selecting the values of R-17, R-19, C-10 and C-11, tube 14 can be made to produce a square wave of a frequency suitable for turning on and off the modulation of transmitter 4.

The plate of tube 18 is connected to positive voltage terminal B through relay 16. The grid is connected to ground through R-24 and R-25 and the cathode is connected to ground through the contacts of relay 23. When the relay 23 is closed by switch 22 plate current will flow in tube 18 and operate relay 16. When relay 16 closes, selector system 6 in Fig. 3 operates. When tube 18 is cut off by a negative voltage on the grid, relay 16 opens and selector 6 is cut off and advances to the next step by spring action.

The plate of tube 19 is connected to positive voltage terminal B through relay 17; the grid is connected to ground through R-24 and R-26. The cathode is grounded through R-21. Plate current will flow in tube 19 and operate relay 17. The contacts of relay 17 operate an indicator

light on the pilots control board, indicating when the transmitter is being modulated. When the negative voltage from tube 14 cuts off tubes 13 and 18, tube 19 is also cut off, switching off indicator light 21. R-22 and R-30 are decoupling resistors and C-13 and C-15 filter capacitors. R-28, R-29 and C-14, C-14A are connected across the contacts of relay 16 to prevent arcing.

Fig. 5 illustrates details of a control unit carried by the controlled planes. The received modulated carrier is applied to a conventional demodulator, not shown, and hence fed to terminal A of plug 24; terminal B of this plug is grounded.

The demodulated signal, which is a pulsed audio frequency, similar to the transmitted audio pulses, is amplified in tube 25, rectified in tube 15a, corresponding in its function to tube 15 in the equivalent section of the control plane control unit, and the resulting pulses, having been amplified in tube 18a, operate the relay 16a. Positive pulses, providing current through the relay solenoid, will close this normally open relay, connecting the 12 volts supplied to terminal B on plug 25a to terminals A and F on plug 26a. Terminal D on plug 25a and terminal E on plug 26a are grounded. Terminal B on plug 26a is permanently connected to terminal B on plug 25a, hence there are always 12 volts applied to this terminal. Plugs 25 and 26 in the control plane unit are similarly wired.

Fig. 5 shows the circuit diagram of control unit 5A used in the receiving planes. The control unit of Fig. 5 will now be described in more detail. The plate of tube 25 is connected to positive voltage terminal B through R-33. Screen voltage is obtained through R-34. The grid is connected to ground through potentiometer R-31 and the cathode is grounded through R-32. Capacitors C-16 and C-18 are bypass capacitors for the screen and cathode resistors respectively. C-19 couples the output of tube 25 to the plate of diode 15a and R-35 is the diode load. When a positive voltage is applied to the plate of diode 15a current will flow to the cathode and through R-37 and R-36 to ground. The grid of tube 18a is connected through a bias battery 52 through R-36 to ground. The cathode of 18 is connected to ground and the plate connected to positive terminal B through relay coil 16a. The contacts of relay 16a controls plus 12 volts for the selector system 6A. Bias battery 52 normally cuts off tube 18a thereby leaving relay 16a open. When a positive voltage is applied to the plate of 15a of sufficient amplitude to overcome the bias voltage of 52, tube 18a will draw plate current and relay 16a will close thereby operating the selector system. Plug 24 is connected to the audio output of receiver 8 and when an audio voltage is obtained from the receiver this is coupled through C-17 to the grid of tube 25 amplified and rectified in tube 15a. Potentiometer R-31 is used for adjusting to the proper value. When this signal is of sufficient amplitude it operates tube 18a which closes relay 16a which in turn controls the selector system. Capacitor R-20 is connected across R-36 to give a time constant for this circuit and prevent spurious noise voltages from operating tube 18a. Resistors R-38, R-39 and capacitors C-21, C-22 are connected across the contacts of relay 16a to minimize arcing.

Fig. 6 shows the selector system and the smoke control, which are identical for control and controlled planes.

The terminals of plug 26B are connected to the

corresponding terminals of either plug 26 or plug 26A, depending on whether it is on the control plane or on one of the other planes. Each positive 12 volt pulse on terminal A serves to advance the selector switch 27 by one step by means of solenoid 20, pushing sprocket wheel 28 ahead, and thereby rotating contact arms 29A, 29B, 29C, and 29E of stepping switch 27. There are 50 contacts on each of the contact arms 29A to 29E of the particular switch illustrated, arms 29A, 29B and 29C being connected in series to provide 150 contacts corresponding to the time intervals 1 to 150 indicated in Fig. 1. These figures are given as examples only and can be varied within wide limits.

Contacts 50, cooperating with each of the first four contact arms, are connected to the selector relay advance coil 30, pushing the armature 30A against the tension exerted by spring 30B, thereby advancing the ratchet wheel 41 by one step so that the lead 32 will be connected to the subsequent contact arm on switch 27.

The 12 volt pulses supplied by terminal F on plug 26B are fed by lead 32 to the contact arm 33A of switch 31. This contact arm applies the pulses to either of contact arms 29A, 29B or 29C, in sequence, depending on its position. As illustrated in the embodiment shown in Fig. 6, the sky writer will have available for writing all contacts on the first three contact arms of switch 27, or 150 contacts, so that a maximum of 150 lines can be produced by each plane.

It will be seen that the 12 volt pulses supplied to the contact arms 29A to 29C are further supplied to the sockets in panel 34, a front view of which is shown in Fig. 2. The plugs 49 in these sockets having been set in each plane according to a predetermined line pattern, only those pulses where connections are provided will pass through leads 49' to lead 35 to operate the smoke valve relay 36 which will open the oil valve 37 for the duration of the pulse.

At the end of each period of writing, the two switches 27 and 31 must be reset to their initial positions. A manually operated reset switch 38 is provided for this purpose, its two contacts providing 12 volts D. C. to the selector reset coil 39 and to the contact arm 29E of switch 27, respectively.

Selector reset coil 39, operating against spring 40, causes the ratchet 41 to be released so that reset spring 42 will rotate switch 31 until spring 42 reaches its contracted position, when contact arms 33A and 33B bridge contacts 1.

If contact arm 29E is in position 1 while the D. C. voltage is applied, nothing will happen. In any other position of contact 29E, however, the D. C. voltage will be applied to the stepping switch advance coil 20, pushing its armature 20A to advance the ratchet wheel 28 by one step. Current through the relay 20 will further cause normally closed switch 43 to open. Opening of the switch 43 will in turn deenergize the relay coil 20, permitting spring 20B to retract the armature 20A and the switch 43 to close again, reestablishing current through the coil 20. This process is repeated until contact arm 29E is in position 1, and the switch 27 is reset to its starting position. Completion of the resetting operation will be indicated by lamp 44 which will light only if both switches 27 and 31 are in their initial positions.

A test switch 45 for the smoke control valve 37 and associated elements is provided so that the pilot can ascertain whether or not the smoke valve and supply channels are in good order.

Depression of test switch 45 will apply 12 volts D. C. to the upper terminal of the valve relay 36 causing the valve to open and smoke to be released.

It will be understood that the switching arrangement and the electronic circuitry shown and described as constituting a particular embodiment of this invention should not be construed as limiting. It is desired that the invention be interpreted as broadly as the scope of the appended claims.

Having thus described our invention, what we claim and desire to secure by Letters Patent is as follows:

1. Apparatus for controlling the flow of a visible trace forming substance emitted by planes flying in formation, comprising a control plane, an audio oscillator in the control plane generating audio frequency oscillations, a pulse generator in the control plane supplying a succession of equal-length pulses, a modulator in the control plane fed by said oscillator and controlled by said pulse generator to generate a pulse-modulated audio frequency oscillation, a transmitter in said control plane fed by said modulator, a plurality of controlled planes, a receiver in each of said controlled planes, a demodulator in said controlled planes connecting to the receivers and restoring the succession of pulses, a direct current supply in each plane, a relay in each plane operated by said succession of pulses, a stepping switch in each plane having one common terminal and a plurality of contacts successively connected to the common terminal when the switch is operated, a supply switch inserted between said direct current supply and said common terminal of the stepping switch in each plane, said supply switch being actuated by said relay in each plane, an actuating mechanism in each plane for the stepping switch, said actuating mechanism being controlled by said relay and adapted to advance the stepping switch by one step each time the relay is operated by one pulse in the succession of pulses, a plugboard with separable connectors leading to each of the plurality of contacts on the stepping switch selectively connecting each contact to a common terminal, and a smoke control mechanism connected to the common terminal.

2. Apparatus for controlling the flow of a visible trace forming substance emitted by planes flying in formation as claimed in claim 1, further comprising a reset mechanism for said stepping switch.

3. An apparatus for writing in the sky comprising a plurality of planes in formation, means for emitting discreet smoke bursts, a control plane having an oscillator for generating sine-wave oscillations, an electronic switch for interrupting said oscillations at equal and regularly spaced time intervals, a transmitter for transmitting said interrupted oscillations, a plurality of controlled planes, each having a receiver for receiving interrupted oscillations, a demodulator in said receivers for transferring said oscillations into audio pulses, a direct current supply in each plane, a relay in each plane operated by said succession of pulses, a stepping switch in each plane having one common terminal and a plurality of contacts successively connected to the common terminal when the switch is operated, a supply switch inserted between said direct current supply and said common terminal of the stepping switch in each plane, said supply switch being actuated by said relay in each plane, an actuating mechanism in each plane for the stepping switch, said actuating mechanism being controlled by said relay and adapted to advance the stepping switch by one step each time the relay is operated by one pulse in the succession of pulses, selective switch means for producing a predetermined smoke pattern and smoke control means connected to said selective switch means for effecting said smoke pattern.
